UNITED STATES PATENT OFFICE.

CLAUDIUS V. BOUGHTON, OF BUFFALO, NEW YORK, ASSIGNOR TO THE BUFFALO SEAL AND PRESS COMPANY, OF SAME PLACE.

SEAL-LOCK.

SPECIFICATION forming part of Letters Patent No. 372,653, dated November 8, 1887.

Application filed January 26, 1887. Serial No. 225,503. (Model.)

To all whom it may concern:

Be it known that I, CLAUDIUS V. BOUGHTON, a citizen of the United States, residing at Buffalo, in the county of Erie and State of New York, have invented certain new and useful Improvements in Seal Locks; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to that class of seal locks in which the locking mechanism is covered by card board or other easily-destructible material, the breaking or destroying of which is necessary in order to separate the locked parts.

It is my object to provide a seal-lock which is not only applicable to sealing the doors of cars, but can be applied equally as well to flexible bags containing money, mail, or other valuables.

With this object in view my invention consists, essentially, of a back-recessed plate containing spring-pressed pivoted catch-plates, and a front plate with oblong openings and provided at its sides with notched spurs adapted to enter sockets in the rear plate and engage with the spring-pressed pivoted catches to lock the two plates together. Between these two plates and over the locking mechanism is placed the card, upon which the necessary inscriptions are so placed as to show through the oblong openings in the front plate. A strip of very thin metal, preferably brass, is placed through the lock or around the bag, and its doubled ends pass down between the card and rear plate, being secured in such position against removal by pins upon one plate, which pass through the metallic strip and enter sockets in the other plate.

I will now proceed to describe definitely the approved manner in which I propose carrying out my invention.

In the drawings, Figure 1 shows my improved seal-lock applied to a money-bag. Fig. 2 shows rear plate with its locking mechanism. Fig. 3 is an end view of the front plate. Fig. 4 is a cross-section taken in the line xx of

Fig. 1, and Fig. 5 is a view of the inscribed card.

Referring to the drawings, a is the rear plate of the lock, preferably square, and recessed or cut out upon one of its faces to make room for the locking mechanism. Within this recess a' is arranged the catch-plates $b b$, each pivoted at b' , and having the inward extensions $b^2 b^2$ lapping beyond each other, with a narrow space between them to allow of the insertion of a key or other device, by means of which they can be turned in opposite directions in unlocking the seal, as will be hereinafter explained.

$c c$ are springs having one of their ends embedded in the plate a , the other ends resting against the catch-plates $b b$. With the aid of the rigid pins $c' c'$, located behind the springs, these springs $c c$ hold the catch-plates $b b$ in the normal position shown in Fig. 2, their edges resting loosely under the projections $a^2 a^2$, extending out over the recess a' .

$d d$ are sockets in the sides of the plate a , adapted for the reception of the notched spurs of the front plate. $d' d'$ are similar but smaller sockets in the plate a , adapted for the reception of pins upon the front plate, and $d^2 d^2$ are small pins or spurs which pass through and hold the card.

e is the front plate of the lock, having the oblong openings e' , formed by the cross-bars e^2 . Centrally arranged upon the under side of this plate at its sides are the beveled spurs e^2 , provided with the inside notches, e^4 , these notched spurs being adapted for engagement with the sockets $d d$ of the plate a .

$e^5 e^5$ are pins upon the under side of the plate e , adapted for engagement with the small sockets $d' d'$ of the plate a .

f is the card adapted to be placed between the plates a and e , the spaces f' being properly inscribed and adapted to show through the openings e' in the plate e .

$f^2 f^2$ are notches in the sides of the card, in which the spurs $e^3 e^3$ rest and prevent the card from being moved from its position.

g is the strip, made of very thin sheet brass, which I employ with my improved seal-lock.

The operation of adjusting the various parts just described and locking the two plates together is substantially as follows: As shown

in Fig. 1, the strip *g* is applied as securing the mouth of a money-bag, it being threaded through slits in the bag, as shown. The loose ends are held together, and in that position are placed upon the rear plate, *a*, in a line with and covering the small sockets *d' d'*, as shown in dotted lines in Fig. 1. The card *f*, preferably of stiff paper, is next placed in a central position upon the plate *a* and over the ends of the strip *g*. Upon these is placed the plate *e*, which is pressed down thereon, the pins *e³* puncturing the ends of the strip *g*, the pins *d²* *d²* puncturing the card, and the notched spurs entering the sockets *d d* of the plate *a*. As the spurs *e³* enter, their beveled ends push aside the spring catch-plates *b b* until the notches *e⁴ e⁴* in the spurs reach the plates *b b* when their side edges are sprung into the notches by the aid of the springs *c c*, thus effectually locking the two plates together with the card and strip securely held between them. The plate *e* can only be disengaged from the plate *a* by moving the catch-plates *b b* out of engagement with the notched spurs *e³* of plate *e*. This could be effected by applying pressure through the card *f* against the edges *b³ b³*, provided they were accessible; but it will be observed by reference to Fig. 2 that the bars *e² e²* of plate *e* (shown in dotted lines) cover these edges *b³ b³* when the two plates are locked, thus effectually preventing tampering with the lock at these points. The only other way of unlocking the plates is by cutting away the card and the ends of the metallic strip to such an extent that the key or tool may be inserted between the extensions *b² b²* of the the catch-plates *b b*, which could be easily detected if done for thieving purposes or by unauthorized parties.

After the seal-lock has been opened by the proper party and the card and strip removed, it is again adapted for use, as before. It can be applied to any purpose for which the seal-locks now in use are adapted.

I claim—

1. A seal-lock comprising a rear plate having a recessed and socketed inner face, spring-held catch-plates having pivotal bearing within said rear plate and adapted to extend partly across the adjacent sockets in said rear plate, said catch-plates having at their inner edges overlapping disconnected extensions, a metallic strip or seal, an address-card having notched edges and resting upon the rear plate, a front plate having a slotted face to permit of the exposure of the address on the address-card, and depending spurs adapted, respectively, to grip the metallic strip and card and to engage the pivoted catch-plates, substantially as set forth. 45

2. A seal-lock consisting of the rear plate, *a*, recessed at *a'* and having the sockets *d d* and *d' d'* in its sides, and the spring-pressed catch-plates *b b²* and *b b²*, pivoted within said recessed portion, and the front plate, *e*, with recesses *e' e' e'* and cross-bars *e² e²*, the notched spurs *e³ e⁴* and *e³ e⁴*, and the pins or spurs *e⁵*, the two plates adapted, as shown, to lock between them the metallic strip *g* and the card *f*, substantially as shown and described. 55

3. A seal-lock consisting of the rear plate, *a*, recessed at *a'* and having the sockets *d d* and *d' d'* in its sides, and the spring-pressed catch-plates *b b²* and *b b²*, pivoted within said recessed portion with their edges extending under the projections *a² a²*, and the front plate, *e*, with recesses *e' e' e'* and cross-bars *e² e²*, the notched spurs *e³ e⁴* and *e³ e⁴*, and the pins or spurs *e⁵*, the two plates adapted, as shown, to lock between them the metallic strip *g* and the card *f*, with the side notches, *f² f²*, substantially as shown and described. 70

In testimony whereof I have signed my name to this specification in the presence of two subscribing witnesses.

CLAUDIUS V. BOUGHTON.
